UNITED STATES PATENT OFFICE.

ERNEST G. RAFF, OF ST. LOUIS, MISSOURI, ASSIGNOR TO LIBERTY ACCESSORIES CORPORATION, OF ST. LOUIS, MISSOURI, A CORPORATION OF MISSOURI.

WHISTLE.

1,289,541.

Specification of Letters Patent. Patented Dec. 31, 1918.

Application filed April 10, 1918. Serial No. 227,764.

To all whom it may concern:

Be it known that I, ERNEST G. RAFF, a citizen of the United States, residing at the city of St. Louis, State of Missouri, have invented certain new and useful Improvements in Whistles, of which the following is a specification.

This invention relates to whistles or signaling devices of the type that is operated by the exhaust gases of automobile engines, and has for its main object to provide a whistle which can be readily attached to the exhaust manifold of the engine and which is adapted to be operated by a portion of the gases that passes through said manifold. Another object is to provide a whistle of the character referred to which emits a soft and pleasing sound, the pitch of which can be varied at the will of the operator.

Another object is to provide a whistle of the character referred to that is accessible for purposes of cleaning, repair, etc. Other objects and desirable features of my invention will be hereinafter set out.

One type of so-called "exhaust horn" or whistle with which I am familiar is adapted to be arranged at the extreme rear end of the exhaust pipe. This type is open to two serious objections, namely, the fact that it is quickly rendered inefficient by accumulations of road dust and mud and the fact that when the entire exhaust gases are diverted from their usual path of travel to operate the whistle considerable back pressure is produced which materially affects the operation of the engine. Another type of whistle is adapted to be operated by the compressed gases in the cylinders of the engine, but has the disadvantage of having to have finely ground and seated valves to operate against the relatively high cylinder pressure, and, furthermore, gives forth a shrill, unpleasant sound, due to the high operating pressure. This type also affects the efficiency of the engine, owing to the fact that whenever the whistle is operated the compression in the particular cylinder with which the whistle is connected is materially reduced.

My improved whistle is connected to the exhaust manifold of the engine in such a manner that only a portion of the exhaust gases passing through said manifold is utilized to operate the whistle, and, therefore, it will be obvious that whenever my whistle is operated the effect will be actually beneficial to the engine, in that said whistle acts virtually as a "muffler cut-out" to relieve some of the back pressure that is caused by the gases passing through the muffler. My whistle comprises few simple parts on which no accurate machine work is necessary, which can be produced at a low cost of manufacture and which can be assembled and installed by unskilled labor.

In the accompanying drawings forming part of this specification, in which like numbers of reference denote like parts wherever they occur,

Figure 1 of the drawings is a vertical sectional view of a portion of an automobile, showing the exhaust manifold of the motor thereof equipped with a whistle constructed in accordance with my invention;

Fig. 2 is an enlarged longitudinal sectional view of the whistle;

Fig. 3 is an elevational view of the elbow member, looking in the direction of the arrows as indicated in Fig. 2;

Fig. 4 is a perspective view of the elbow member; and

Fig. 5 is a perspective view of the plunger.

Briefly described, my invention consists in an automobile whistle provided with means controlled by the operator of the automobile for varying the pitch of the sound emitted therefrom and which is constructed in such a manner that it can be easily and quickly installed on the exhaust manifold of various styles of internal combustion engines.

Referring to the drawings, which illustrate one form of my invention, A designates an internal combustion engine provided with the usual exhaust manifold B through which the discharged gases pass on their way to the muffler (not shown).

My improved whistle comprises a tube or

cylinder 1 that is carried by a member 2 which is in communication with the interior of the exhaust manifold.

The whistle organization includes a substantially L-shaped elbow member 2, which is provided with a reduced lower end having exterior screw threads 3, there being a shoulder 4 at the juncture of the reduced end and the other part of the elbow member. 5 The elbow member is provided with a port 5 extending axially therethrough, the upper end of said port being restricted to form a throat 6, said restriction being formed by an abutment 7 preferably formed integrally 10 with the elbow member, so that the upper end of the elbow member presents a solid front with the exception of the restricted throat 6. An annular groove 8 is formed in the solid front face of the elbow member, into which one end of the tube is secured by means of a suitable fastening device, such, for instance, as set screw 10. The other end of the tube is spun or otherwise suitably drawn together, so as to leave a small orifice 15 11, to be hereinafter referred to, said partially closed end being for the purpose of forcing the tone. The edge of the walls around the opening 11 is rounded by bending the edges of the metal back, as at 12. 20 Within the tube a plunger 13 is slidably mounted and is provided with a lug 14, to which one end of the operating cord or cable 15 is secured, the other end of the cable extending to a point within the automobile 25 to which the whistle is attached for convenience of operation by the driver of the machine. A spring 9 is mounted in the tube 1 back of the plunger 13, and tends normally to force the plunger toward the elbow member 2. 30

The plunger 13 is provided with an annular lug 17, which is adapted to fit in a space 18, within groove 8, said lug 17 having a flat throat-closing portion 16, which is 35 adapted, when the plunger is in normal position to enter and close the restricted throat 6, which is flat on one side, so as to be adapted to coöperate with flat part 16.

Thus the abutment 7 is encircled within 40 the recess formed in the plunger 13 between the lugs 16 and 17 when the plunger is in its normal closed position, whereby a tight joint is formed between these parts when they are 45 in closed position, thereby preventing the exhaust from the manifold operating the signal. Of course, it will be understood that the top face of the abutment 7 is flat, as is usual in whistles.

When the cord or cable 15 is pulled by 50 the operator in a direction to compress the spring 9, the piston valve or plunger 13 is withdrawn from the throat 6 and uncovers the exit port 19 of the tube and allows a portion of the gases from the exhaust pipe to

pass through said throat into the tube, from 65 which the gas escapes through the exit port 19 of the tube 1 and produces a musical whistling sound. By moving the plunger or piston valve 13 toward or away from the abutment 7, the pitch of the sound emitted 70 from the exit port 19 can be varied at will, and when the operator releases the cord 15 the plunger 13 will, under the influence of the spring 9, return to its normal closed position, thereby closing throat 6, and thus 75 automatically prevent the exhaust gases from acting on the sound-producing means of the whistle.

In practice I arrange the operating end 80 of the cable or cord 15 adjacent the steering wheel of the automobile and have the said cord pass through suitable eyelets or pulleys 20 arranged in the dash of the automobile, but the particular manner of leading the operating cable to within convenient reach 85 of the driver of the automobile can be varied at will.

In the drawings I have shown the whistle as being arranged in a substantially horizontal position on the exhaust manifold or 90 pipe, but it is obvious that said whistle could be arranged in an inclined position without changing the mode or result of operation.

From the above it will be seen that I have devised a whistle for automobile engines 95 that is easily accessible for the purpose of cleaning, repairing, etc.; that is not exposed to road dust and mud; that will emit a pleasing musical sound, owing to the fact that it is operated by the gases in the exhaust pipe which are of only a few pounds pressure; a whistle in which the pitch of the sound emitted therefrom can be varied at will of the operator; that comprises few and simple parts that can be manufactured 105 cheaply; and which can be readily installed on the exhaust manifold or pipe or on an automobile engine by simply threading a hole in the exhaust manifold or pipe at any accessible point between the engine and the 110 usual manifold.

Having thus described this invention, I hereby reserve the benefit of all changes in form, arrangement, order, or use of parts, as it is evident that many minor changes 115 may be made therein without departing from the spirit of this invention or the scope of the following claim.

I claim:

A whistle of the character described, comprising a hollow member formed on one end with an annular groove, the inner wall thereof having a flat surface, the said end of the hollow member having an inlet opening one wall of which is flat and in alinement with the flat portion of the flange, a tubular member seated in the annular groove and formed with an outlet opening adjacent the inlet

opening, a reciprocal valve in the tubular member, said valve having an annular flange at its inner end, the inner edge of said flange having a flattened portion to register with 5 the flat surface in the annular groove when the flange is seated in said groove, and means for withdrawing the flange from the groove

whereby when said valve is moved the pitch tone of the whistle will be altered by the flat surfaces and the distance the inner end of 10 the valve is from the groove.

In testimony whereof I hereunto affix my signature.

ERNEST G. RAFF.
